UNITED STATES PATENT OFFICE.

GIOVANNI STUCKY, OF VENICE, ITALY.

DRYING APPARATUS.

SPECIFICATION forming part of Letters Patent No. 565,522, dated August 11, 1896.

Application filed February 13, 1895. Serial No. 538,253. (No model.)

To all whom it may concern:

Be it known that I, GIOVANNI STUCKY, a citizen of the Republic of Switzerland, residing at Venice, in the Kingdom of Italy, have 5 invented certain new and useful Devices for Drying Powderous, Mealy, and Grainy Substances, as Flour, Bran, Grains, &c., of which the following is a specification.

My invention has relation to driers; and it 10 consists in certain improvements which I will now describe in detail, reference being had to the accompanying drawings, in which—

Figure 1 is a vertical section on or about on line 2 2 of Fig. 2, Fig. 2 being a section 15 on or about on line 3 3 of Fig. 1, looking toward the left. Fig. 3 is a more or less schematic view of the driving mechanism. Fig. 4 is a fragmentary elevation illustrating the means for driving the drier and its fan- 20 shaft from the main suction-fan shaft; and Figs. 5 and 6 are fragmentary longitudinal and vertical sectional views, respectively, of the drier, drawn to an enlarged scale.

In the above-described drawings I have 25 illustrated two driers in connection with a source of air supply as an example, and the arrangement shown will readily suggest to the skilled mechanic the connection with a source of air supply of a greater or less number 30 of such driers. In said arrangement a suction and force fan casing or housing *o* is arranged below an elevated platform *P*, the fan *p* in said casing drawing air from a heater, for instance, (not shown,) through a trunk *T* 35 and forcing such air through suitable branch trunks *n* and *m* to the driers *A*.

As the construction of both driers is the same, a description of the construction of one will suffice.

40 The drier *A* consists of two stationary cylindrical heads *b b*, both connected at their lower end with the air-supply trunk *m* and provided with an axial bearing for a shaft *i*, revolvable in bearings in suitable standards 45 on the platform *P* and carrying a belt-pulley *r'*. The heads *b* are further provided with an outwardly-flaring circular flange *b'*, that serves to close the ends of the outer cylinder *e'* of the drier, presently referred to.

50 An open-ended cylinder *e*, constructed of a foraminous material, as a wire fabric or perforated sheet metal, is provided near said

open ends with supporting-arms *g*, radiating from an axial bearing for and rigidly secured to the aforesaid shaft *i*, which also carries 55 two suction-fans *k*, one at each end of the cylinder *e*, and an intermediate distributing-fan *l*, whose blades extend nearly the full length of the space between said suction-fans. An open-ended outer cylinder *e'* of 60 substantially the same length as the cylinder *e* encompasses the latter, the open ends of the annular space between the two cylinders, which constitutes the drying-chamber, being closed by the aforesaid outwardly-flaring 65 flanges *b'* on the drier-heads *b*. The material to be dried is fed to said drying-chamber through a feed-trunk *c* at one end and discharged into a discharge-trunk *d* at the opposite end, said discharge-trunk being in 70 communication with the drying-chamber through a suitable opening in the encompassing flange *b'* of one of the drier-heads *b*. The outer cylinder *e'* is or may also be constructed of a foraminous material, as a wire fabric or 75 perforated sheet metal, the fineness of the mesh or perforations of both cylinders depending upon the fineness of the material to be dried.

If the outer cylinder *e* is constructed of a 80 non-foraminous material, a suitable outlet for the air is provided, which can very conveniently be done by providing the flange *b'* of the drier-head opposite to the inlet-port for the material with an air-outlet duct *K*, 85 as shown in Fig. 5.

In order that the material may be gradually and continuously translated from the feed to the discharge end of the drying-chamber, I provide the outer cylinder with spiral 90 blades *f*, preferably of great pitch, that form a screw-conveyer. At one end the outer cylinder *e'* is secured to a ring, a portion of which is of increased thickness and of such configuration as to perform the function of a belt-pulley *t*, and said outer cylinder is supported 95 on rollers *h*, Fig. 6, at both ends.

The inner cylinder *e* revolves at a comparatively high speed, while the outer cylinder *e'* revolves at a comparatively low speed, the 100 effect of the different speeds relatively to the operation of the screw-conveyers *f* on the outer cylinder being the same as if one of said cylinders were stationary. To this end the

small pulley r' on shaft i of cylinder e is belted to a comparatively large pulley q on shaft s of fan p , while the cylinder e' , through its ring-pulley t , is belted to a small pulley r on said shaft s , as shown in Fig. 3. The blades f on the inner periphery of the cylinder e are so arranged as to perform the function of a screw-conveyer and to slowly translate the material from the feed to the discharge end of the drying-chamber, and at the same time to take up and distribute said material over the inner cylinder e in the form of a thin sheet or scatter the same over said cylinder, according to the nature of said material, whereby the latter is thoroughly exposed to the air-currents and rapidly dried.

It will readily be seen that the improvements described lie, essentially, in the means for bringing the material into intimate contact with the air, namely, in a scattered condition, the material being constantly kept alive within the drying-chamber, not only by the operation of the conveyer, but by the action of the air-currents, and is thereby, for the greater part of the time, practically held in suspension in a drying-atmosphere, thereby insuring its rapid and thorough desiccation, so that certain materials need not be passed through the driers more than once.

Of course other means than those described may be resorted to for imparting a differential speed to the fans and drier-cylinders, while the construction of the latter and the arrangement of the means for supplying air thereto may also be modified without departing from the spirit of my invention.

Having thus described my invention, what I claim as new therein, and desire to secure by Letters Patent, is—

1. A drier comprising two concentrically-arranged and independently-revolvble open-ended cylinders, the inner cylinder being perforated whereby a drying-chamber is formed between them, stationary heads for said cylinders, air-ports in said heads leading to the inner cylinder, forcing devices for forcing air into said inner cylinder, distributing devices within such cylinder for driving the air through its perforations into the drying-

chamber, feed and discharge devices arranged to feed the material to the drying-chamber at one end and discharge it from the other end, and means for moving such material about the inner cylinder from said feed to said discharge end of the cylinder, substantially as and for the purpose set forth. 50 55

2. In a drier the combination with two concentric foraminous cylinders forming between them a drying-chamber, means for feeding the substance to be dried to said chamber at one end and discharging it at the opposite end, a distributor and conveyer movable with the outer cylinder for distributing the substance to be dried over the inner cylinder and conveying said substance from the feed to the discharge end of the drying-chamber, a suction-fan at each end of the inner cylinder, a distributing-fan intermediate of said suction-fans, and driving mechanism for driving the inner cylinder and fans at a greater speed than the outer cylinder, for the purpose set forth. 60 65 70

3. In a drier, the combination with two concentric foraminous cylinders arranged to form a drying-chamber between them, means for feeding a substance to the chamber at one end and discharging the same at the opposite end, screw-conveyer blades f secured to the inner periphery of the outer cylinder operating to distribute or scatter the substance over the inner cylinder and convey such substance from the feed to the discharge end of the drying-chamber, a suction-fan k at each end of the inner cylinder, a distributing-fan l intermediate of said suction-fans, a suction and forcing fan, and suitable ducts connected with the case of the last-named fan and leading to the opposite ends of the inner cylinder, and driving mechanism for revolving the inner cylinder and fans at a greater speed than the outer cylinder, for the purpose set forth. 75 80 85 90

In testimony whereof I hereunto sign my name, in the presence of two subscribing witnesses, this 14th day of January, 1895.

GIOVANNI STUCKY.
